(57) CLAIM

The ornamental design for a protective face mask with goggles and headstraps, as shown and described.

DESCRIPTION

FIG. 1 is a perspective view showing the top, left side and front of a protective face mask with goggles and headstraps which forms our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
